UNITED STATES PATENT OFFICE.

WILLIAM S. HADAWAY, JR., OF NEW ROCHELLE, NEW YORK, ASSIGNOR TO THE CUTLER-HAMMER MFG. CO., OF MILWAUKEE, WISCONSIN, A CORPORATION OF WISCONSIN.

FLUID-HEATER.

1,281,157.

Specification of Letters Patent.

Patented Oct. 8, 1918.

Original application filed January 28, 1913, Serial No. 744,725. Divided and this application filed February 28, 1914, Serial No. 821,817. Renewed December 20, 1915. Serial No. 67,954.

To all whom it may concern:

Be it known that I, WILLIAM S. HADAWAY, JR., a citizen of the United States, residing at New Rochelle, in the county of Westchester and State of New York, have invented new and useful Improvements in Fluid-Heaters, of which the following is a full, clear, concise, and exact description, reference being had to the accompanying drawing, forming a part of this specification.

This invention relates to improvements in electric fluid heaters.

The present application is a division of original application Serial No. 744,725, filed January 28, 1913, issued as Patent No. 1,258,767, dated March 12, 1918.

One of the objects of the invention is to provide an improved fluid heater in which the electric heating units may be readily removed without dismantling the heater.

Another object is to provide an improved construction for fluid heaters by means of which a heater of any desired capacity may be quickly assembled out of units of standard size and shape.

Another object is to provide a heater which may be inexpensively manufactured and quickly and easily assembled.

Another object is to provide a heater in which the parts may be readily removed and replaced for inspection and repair.

Other objects and advantages of the invention will hereinafter appear.

The accompanying drawings illustrate an embodiment of the invention. The views of said drawings are as follows:

Fig. 1, is a sectional elevation of a four unit heater.

Fig. 2, is a side elevation of the heating units.

Fig. 3, is a sectional view on the line 3—3 of Fig. 1, with the resistance units removed from their containers.

Fig. 4, is a sectional view on the line 4—4 of Fig. 1.

The heating chamber comprises a tubular member 1, preferably a metal cylinder provided with a cap 2 having screw threaded engagement therewith, the latter having a screw threaded opening 3 adapted to be connected to a pipe. The cylinder has secured to the lower end thereof a ring 4 made preferably of cast metal and having screw

threaded engagement therewith; said ring 5 having a screw threaded opening 5 for the attachment of another pipe. The ring 4 has secured thereto an additional ring 6 having both vertical and horizontal flanges as shown, said ring serving to secure between itself and the ring 4 a metal disk 7, and a washer or gasket 8 preferably of rubber. These parts are held in position by the screws 9, which pass upward through the horizontal flange of the ring 6 into the ring 4, whereby the metallic disk is firmly clamped in place and a water tight connection is secured. A metallic casing 10 is secured within the lower part of the ring 6, by means of suitable screws 11.

The disk 7, which is made preferably of copper, has a plurality of openings therein, four in number in the present instance, through which pass sheet metal containers 12. Of course, a greater or less number of containers may be employed, depending on the desired heating capacity.

Said containers are each closed at their upper end, but open at their lower end whereby an electric heating unit may be slipped therein from below, being thereby incased in a water tight jacket. Said heating units are not described specifically herein, but I preferably employ units constructed in accordance with the disclosure in my co-pending application hereinbefore mentioned, in which a slotted metal ribbon is employed. The projecting ends 13 of said ribbon are clamped together below the metal disk as shown in Fig. 2, the individual ends 14 being separated from each other by mica spacers 14. A screw threaded stud 15 passes through suitable openings in the metal insulation, nuts 16 being employed to clamp the parts together. Suitable U shaped jumpers 17 are also employed, whereby the circuit may be completed to the individual units, and the circuit connections may be readily varied if desired. Suitable terminal members 18 are also clamped between the nuts 16 and are so disposed as to give the desired circuit connections. Screws 19 are employed to clamp the circuit conductors to the terminal members 18, said circuit conductors entering through the opening of the casing 10. The terminal members 18 are preferably spread out radially as shown in Fig. 1, to facilitate the securing of the con-

ductors beneath the heads of the terminal screws 19.

It will be seen that the containers 12 are supported by the metal diaphragm, and hence may be readily assembled within the heating chamber and as readily removed. They may, however, be reinforced at their upper ends by means of a suitable cross strip 20, the latter being secured to the inner 10 walls of the tube 1. A faucet or stop cock 21 is mounted in a suitable opening in the ring 4, whereby the heated fluid may be drawn off if desired.

In operation, the heating chamber is ordinarily in communication with a piping system through which the fluid flows, the fluid entering through the opening 5 and leaving through the opening 8 whereby it passes upwardly around the containers and 20 is heated by the heating units, thereby insuring circulation in the direction indicated. The piping system may be connected with a suitable reservoir, whereby the heater may be used to heat a body of liquid much in excess of the capacity of the heating chamber. Inasmuch as the heating units are inserted into their containers from below the supporting disk 7, it is apparent that any one or all of said units may be removed and 25 replaced at will by simply disconnecting the various terminal members, but without disturbing the water tight connection between the containers and their supporting disk. Furthermore, the heating capacity of the 30 device may be varied by removing the disk or head and substituting in its place one having a greater or less number of containers and heating units. The circuit terminals being arranged within the casing 10 are 35 protected thereby, but access thereto may be had readily by removing said casing. Inasmuch as the device is supported by the piping with which it is connected and not by said casing, which constitutes the lowest 40 part thereof, the removal of said casing may be conveniently accomplished.

It is to be understood that I do not desire to limit myself to the details of construction described and illustrated, except where 45 limitations are imposed in the appended claims.

Having thus described my invention what I claim as new and desire to secure by Letters Patent of the United States is:

55 1. A fluid heater comprising a fluid receptacle having an opening in the wall thereof, a tubular member secured to said wall at said opening and extending into said receptacle, an electric heating unit fitting 60 within said tubular member, said heating unit being longer than said tubular member, whereby a portion thereof is not inclosed by said member, circuit terminals carried by

said uninclosed portion and a casing associated with said fluid receptacle for inclosing 65 said terminals.

2. A fluid heater comprising a fluid receptacle having an opening in the bottom wall thereof, a tubular member closed at its upper end, and connected at its lower end 70 to said bottom wall at said opening, an electric heating unit fitting within said tubular member throughout substantially its entire length and projecting downwardly below said receptacle, circuit terminals carried by the projecting end of said unit, and a casing associated with the lower end of 75 said receptacle, within which said circuit terminals are housed.

3. An electric water heater comprising a 80 heating chamber, a plurality of metallic containers passing through the bottom wall thereof and supported thereby, each container being open at its lower end, a heating unit fitting within each of said containers, 85 whereby any of said units may be removed by drawing it downwardly therefrom, circuit terminals carried by said heating units and means for drawing off the heated liquid from said chamber. 90

4. A fluid heater comprising a heating chamber having side walls, a cap and a bottom diaphragm, a plurality of sheet metal containers passing upwardly through said diaphragm into the heating chamber, a 95 plurality of electrical heating units arranged within said containers, each heating unit having a sliding fit in the corresponding container, circuit terminals carried by said heating units below said diaphragm and 100 means permitting the flow of fluid through said heating chamber.

5. An electric water heater comprising a cylindrical tube, a cap having screw threaded engagement with the top thereof, a ring 105 secured to the lower end thereof, a diaphragm clamped between said ring and said cylindrical tube, a plurality of substantially parallel sheet metal containers supported by said diaphragm and extending substantially to the top of said tube, each of said containers being closed at the top and opening through said diaphragm, an electric heating unit removably secured within each of said containers, circuit terminals carried 110 by said units below said diaphragm, an inclosing casing for said terminals secured to said ring, and means for drawing off the fluid from said chamber. 115

In witness whereof, I have hereunto subscribed my name in the presence of two witnesses.

WILLIAM S. HADAWAY, Jr.
